UNITED STATES PATENT OFFICE.

GEORGE E. KNEPPER, OF ALTOONA, PENNSYLVANIA.

RAILWAY CAR.

Application filed February 3, 1921. Serial No. 442,320.

To all whom it may concern:

Be it known that I, GEORGE E. KNEPPER, a citizen of the United States, residing at Altoona, in the county of Blair and State 5 of Pennsylvania, have invented certain new and useful Improvements in Railway Cars, of which the following is a specification.

This invention relates to railway box cars, and has for its primary object improved 10 means of stiffening the ends of cars, and to this end invention contemplates an integral box car end sheet having struck up stiffening angles therein, each of which is adapted to add rigidity to the car end.

15 Another object of this invention is to provide a car end stiffening sheet that is easily made and applied to car ends and can be readily removed for repairs in case the car end is damaged. In this connection it will 20 also be understood that while the stiffening sheet proposed by the present invention is particularly adapted for use in connection with the ends of cars, it may also be applied to the car sides when desired to stiffen and 25 reinforce the same also.

With these and other objects in view which will be more readily apparent as the nature of the invention is better understood, the same consists in the novel construction, 30 combination and arrangement of parts as will be hereinafter fully illustrated, pointed out, and claimed.

It will be quite readily understood by those skilled in the art to which this invention 35 belongs that the same is quite susceptible to various changes and modifications without departing from the spirit or scope of the invention, but a preferred and practical embodiment is shown in the accompanying drawings, in which:—

Fig. 1 shows an elevation of a railway box car having my invention applied thereto and shows the manner of attaching the brake staff and car end ladders over the 45 stiffening angles.

Fig. 2 shows a part section of the car end shown in Figure 1, and shows the location of the car end structure with reference to the applied stiffening sheet.

Fig. 3 shows an enlarged cross section of the car end stiffening sheet as applied to the car shown in Figure 1 of the drawings.

Fig. 4 shows a modified form of constructing the stiffening angles on the car end 55 sheet.

Fig. 5 shows a further modification of the

construction shown in Figure 3 of the drawings.

Similar reference numerals refer to similar parts throughout the several figures of 60 the drawings.

In carrying out this invention, no radical change is contemplated in the car end construction, and to this end I construct a car end sheet designated by the numeral 10, having a plurality of struck up integral angle portions 11 which are shown in Figure 1, to run horizontally across the end of the car, although this is not an essential feature of the invention, as these angled portions 65 can readily run in a diagonal direction, which would greatly facilitate the removal of snow and ice from the car end.

In the manufacture of these car end stiffening sheets, I use a flat plate 12, which 70 I perforate with a punch leaving an outward projecting stiffening flange 13, on the outer surface 14 of the sheet. This construction stiffens the car against end shocks 75 which come from buffing strains set up 80 within the car or adjacent cars.

A modification of the above method of forming the sheet is shown in Figure 4, which contemplates bending downward the outer end 15 of the flanged portion of the 85 sheet shown in Figure 3 of the drawings. This construction has the effect of shunting off the rain and snow that may be blown down against the end of the car and will prevent to a great extent the decay 90 of the car end structure as well as to prevent undue rust of the car end stiffening sheet.

The channel shape shown in Figure 5 is another means of stiffening the end sheet 95 and has the advantage of giving a good rigid section from a light end sheet.

In applying this sheet to a railway box car, the usual hand brake wheel 16, and rod 17 are retained in their usual place as well 100 as the end ladder 18, and foot board supports 19 which are attached to the outer sheet of the car end. Figure 2 shows this improved car end sheet applied to a car having a wood end finish but this stiffening angled sheet is readily applicable to any car box end where both strength and 105 rigidity are required.

Having thus described my invention, what I claim and desire to be secured by 110 Letters Patent is:

1. A stiffening member for the outside

surface of car walls consisting of a metallic sheet having a plurality of reinforcing flanges punched out therefrom leaving openings in the sheet where the flanges have 5 been displaced.

2. A stiffening member adapted to be fitted to the outside surface of a car wall consisting of a metallic sheet slitted at spaced intervals to provide parts that are 10 bent to provide a plurality of angularly disposed stiffening flanges.

3. A reinforcement for the walls of cars

and the like consisting of a body of sheet metal having a plurality of reinforcing flanges struck outwardly therefrom to stiffen 15 the body and leaving openings in the body sheet where the reinforcing flanges are struck outwardly therefrom.

In testimony whereof I hereunto affix my signature in the presence of two witnesses. 20

G. E. KNEPPER.

Witnesses:

E. L. GROFF,

A. J. LEEK.
